Primary Examiner—Raphael Barkai
Attorney, Agent, or Firm—Oppenheimer, Wolff & Donnelly LLP**[57] CLAIM**

The ornamental design for a top of a car, as shown and described.

DESCRIPTION

FIG. 1 is a top plan view of the top of a car showing the keyboard showing my new design; and,

FIG. 2 is a perspective view thereof.

The broken lines shown in FIGS. 1 and 2 are for illustrative purposes only and form no part of the claimed design.
